United States Patent Office

Des. 178,663
Patented Sept. 4, 1956

178,663

CLIMBING TOWER

Isadore Horowitz, Shreveport, La., assignor to Universal Manufacturing Co., Inc., Shreveport, La., a corporation of Texas

Application March 9, 1956, Serial No. 40,531

Term of patent 14 years

(Cl. D34—5)

The single figure is a perspective view of a climbing tower, showing my new design.

I claim:

The ornamental design for a climbing tower, as shown.
